UNITED STATES PATENT OFFICE.

WILLIAM MARLOW, OF NEW YORK, N. Y., ASSIGNOR TO STANDARD KNITTING MILLS COMPANY, A CORPORATION OF NEW YORK.

UNION SUIT.

1,105,677.

Specification of Letters Patent. Patented Aug. 4, 1914.

Application filed February 27, 1913. Serial No. 751,015.

To all whom it may concern:

Be it known that I, WILLIAM MARLOW, a citizen of the United States, and a resident of the city of New York, State of New York, have invented certain new and useful Improvements in Union Suits, of which the following is a description.

My invention relates to union suits and is particularly applicable to knitted garments, of which the basis is a tube of knitted material, such as formed upon the ordinary circular knitting machine, and has for its object the formation of a bifurcated garment from such a tube with the least possible number of seams and with the least waste of material.

My improved garment dispenses entirely with horizontal seams, which are annoying to the wearer and which are likely to open, and entirely eliminates gussets and other small pieces, the seams attaching which to the main portions of the garment are particularly likely to cause discomfort and to rip.

The method used in making my improved garment is such that a minimum amount of material is required, and it can be formed in a much shorter time and by much less skilled labor and with much less waste than the garments manufactured heretofore.

In the drawings which accompany this specification, Figure 1 is a side view of my improved union suit, and Fig. 2 a section thereof on the line 2--2 of Fig. 1. Figs. 3 and 4 are diagrammatic views showing the method of manufacture and the general outline of the parts which make up the completed suit.

Starting with a tube of material, the process of manufacture is as follows: Cuttings are made at 1--1 to form the sleeves and at 2 to form the neck. The tube is then slit longitudinally as at 3, to a point about at

the waist of the garment, thus forming two bifurcated portions 4--4. The bifurcated portions 4--4 are then spread apart and two triangular pieces 5 are inserted therein, as shown in Fig. 1. The lowermost portion of the triangular pieces 5 are then slit as at 6. The garment is then sewn together by sewing the outer edges 7--7 to the edges of the slit 3, and by sewing the corresponding edges of the slits 6 in the two triangular pieces 5, together. There are, therefore, only six seams in the garment, being seams (see Fig. 1) 8, 9, 10 and 11, and two seams on the reverse side which correspond to the two seams 8 and 9. It will thus be seen that all of the seams are longitudinally disposed in the garment and that a very small number thereof are required to hold it together.

While I have only shown one form my invention may take, it is obvious it may take others without departing from the spirit of my invention, and I, therefore, do not desire to confine myself by the precise form shown and described.

What I claim and desire to secure by Letters Patent is—

A bifurcated garment comprising a tube of fabric having its front and back slit to the waist line and two triangular pieces, the side edges of each triangular piece secured to the edges of the front and back slits respectively of the tube, each triangular piece slit a short distance on the vertical center line from the bottom, and the edges of the slit of one piece secured to the corresponding edges of the other piece.

In witness whereof I have hereunto set my hand in the presence of two witnesses this 24th day of February, 1913.

WILLIAM MARLOW.
